(57) **CLAIM**

The ornamental design for an injector shield, as shown and described.

DESCRIPTION

FIG. 1 is a perspective view of an injector shield, showing our new design;

FIG. 2 is a side view thereof;

FIG. 3 is a front view thereof;

FIG. 4 is a rear view thereof;

FIG. 5 is side view thereof;

FIG. 6 is a bottom view thereof; and,

FIG. 7 is a perspective view thereof.

The broken lines in FIGS. 1-7 are for the purpose of illustrating environmental structure and form no part of the claimed design.

Stippling is used in FIGS. 1-7 to indicate a frosted, translucent appearance.
